UNITED STATES PATENT OFFICE.

VIGGO DREWSEN, OF NEW YORK, N. Y., AND LAURITZ J. DORENFELDT, OF TRONDHJEM, NORWAY.

PROCESS OF UTILIZING SULFITE LYES.

SPECIFICATION forming part of Letters Patent No. 726,036, dated April 21, 1903.

Application filed November 25, 1901. Serial No. 83,649. (No specimens.)

To all whom it may concern:

Be it known that we, VIGGO DREWSEN, residing in New York, borough of Richmond, and State of New York, and LAURITZ J. DORENFELDT, residing in Trondhjem, in the Kingdom of Norway, both citizens of the Kingdom of Norway, have invented certain new and useful Improvements in Processes of Utilizing Sulfite Lyes, of which the following is a specification.

This invention relates to certain improvements in the process of utilizing sulfite lyes, for which Letters Patent were granted to us on March 7, 1899, No. 620,755, said improvements being designed with a view of simplifying and cheapening the process and adapting the same for use in sulfite-pulp mills, which are run in connection with and in proximity to soda-pulp mills.

We have found by practical tests in sulfite-pulp mills that the process heretofore patented could be simplified when the waste liquor from soda-pulp mills was employed for working up the spent liquor of the sulfite-pulp mills. We have also discovered that when the spent liquor from sulfite-pulp mills was utilized by our patented process, even with an excess of alkali, acid condensations are produced which corrode the concentrat-

30 ing apparatus, for the reason that when the temperature, and consequently the pressure in the boiler in which the spent liquor is concentrated, rises to a high temperature vapors are given off which contain aldehydes that are decomposed when mixed with steam of high temperature into alcohols and acids, and as the latter cannot be neutralized in the steam-space of the boiler they are carried on with the condensed water, and consequently

40 corrode the iron and the multiple-concentrating apparatus. We have found that this generation of acids can be considerably decreased when the temperature or the pressure in the boiler is kept down; but this improves the efficiency and economy of the concentrating effect. We have further found that where the spent liquor from a soda-pulp mill is obtainable the spent liquor from a sulfite-pulp mill can be utilized with this alkali line liquor without any formation of acid taking place in the concentrating plant. In

other words, the spent liquors from both mills—sulfite and soda pulp mills—can be utilized to advantage in our improved process.

While in our former process referred to recovered soda (soda-ash) was mixed with the sulfite lye, we now mix therewith the spent lye from the soda-pulp mill. The theory of the new process is that the sodium sulfids contained in the lye from the soda-mill react with the salts of the organic sulfonic acids contained in the sulfite lye and prevent thereby the formation from organic compounds in the lyes of the objectionable aldehydes.

It is a well-known fact that in evaporating the spent liquor from a soda-pulp mill there is always a loss of at least ten per cent. of soda-ash, while when the spent liquor from a soda-pulp mill is worked up with the spent liquor from a sulfite-pulp mill, which latter works with sodium-bisulfite liquor, and both liquors are evaporated together the sodium contained in the spent liquor from the sulfite-mill is sufficient to cover the loss of soda-ash from the soda-pulp mill, so that there is no additional expense for soda for the sulfite-pulp mill, inasmuch as the soda used in this mill is recovered and utilized over again in the soda-pulp mill. Consequently by carrying on the evaporation of the spent liquors from a soda-pulp mill mixed with those of a sulfite-pulp mill a very economical process is obtained by which the spent liquors of both mills are utilized and at the same time the pollution of the water-courses in the neighborhood of the mills effectively prevented.

For this purpose our invention consists of a process of neutralizing the waste or spent liquors of sulfite and soda pulp mills by first neutralizing the waste liquor from one mill with the sodium-containing liquor from the other mill; second, concentrating the neutralized liquors; third, burning concentrated liquors; fourth, leaching the residuum; fifth, treating the solution with burnt lime, so as to render it caustic, and then draining off the clear liquor containing the soluble sodium salts for use as cooking liquor in the soda-pulp mill.

Our process is practically carried out as follows: The spent cooking liquor from a sulfite-pulp mill which contains sodium bisulfite

is neutralized by an equal quantity of the spent liquor from a soda-pulp mill, containing caustic sodium compounds. The water contained in the mixture of the two liquors 5 is then evaporated in a steam-boiler, vacuum-pan, or other suitable concentrating apparatus, and the residuum thus obtained burned or calcined in a suitable calcining-furnace. The hot gases which are developed by the 10 combustion are carried off and utilized for heating purposes, preferably for heating the boiler or the vacuum-pan itself, while the inorganic residuum is leached with water. The solution thus obtained is treated with 15 burnt lime, so as to render it caustic, and is then drawn off and added to the cooking liquor of the soda-pulp mill, the solution containing all the soluble sodium salts.

Our improved process has a special advantage 20 in such cases where sulfite and soda pulp mills are run in one establishment or in close proximity, so that the spent liquors from both mills are available for use. In this case the spent liquors from both mills can be utilized to great advantage by a comparatively 25 simple process, the spent liquor from one mill being utilized for working up the spent liquor of the other mill, the resulting

liquor containing all the soluble sodium salts, which are then returned to the soda-pulp mill 30 for being utilized as cooking liquor in the same.

Having thus described our invention, we claim as new and desire to secure by Letters Patent—

The process herein described of utilizing the waste liquors of sulfite and soda pulp mills, which consists in neutralizing the sulfite-mill liquor containing salts of organic sulfonic acids with the liquor from the soda-pulp mill 40 containing sodium sulfid, concentrating the neutralized liquor, calcining the concentrated liquor, leaching the residuum obtained thereby, treating the solution thus obtained with burnt lime, and draining off the soluble 45 sodium salts for further use, substantially as set forth.

In testimony that we claim the foregoing as our invention we have signed our names in presence of two subscribing witnesses.

VIGGO DRESEN.
LAURITZ J. DORENFELDT.
